FLOOR FASTENING

Abbott W. Lawrence, Milton, Mass., assignor, by direct and mesne assignments, to Fisher H. Nesmith, Cambridge, Mass., as trustee

Application July 19, 1934, Serial No. 735,979
Renewed November 28, 1939

4 Claims. (Cl. 20—8)

This invention relates to flooring and the like, including the covering and finishing of floors, walls, ceilings, etc., by wood or other suitable materials in block or strip form, and the primary object of the invention is the provision of an improved and more economical flooring and flooring material and improved means for laying and holding the same in place.

In one aspect the invention relates to parquet flooring and to an improved parquet flooring block. Parquet flooring blocks are constructed of a plurality of independent pieces joined together to form blocks of any desired configuration, and various means, such as gluing and the use of tongue and groove connections, as in Patent No. 1,477,813, have heretofore been devised for holding the pieces together in block form. As far as I am aware, all such means heretofore known have had various limitations and objections. I have devised improved and relatively simple means for performing this function in a manner eliminating these objections and limitations and producing a superior parquet block more economically than has been heretofore possible, and such accomplishment comprises one object of the invention.

An important feature of the invention relates to a new and inexpensive clip or fastener element for securing the pieces together into block form. The fastener which I have developed may be economically constructed from flat metal strap material merely by cutting the latter into short lengths and striking up retaining bars on the ends thereof. The cooperating edges of the block or flooring pieces are recessed to receive these fasteners and each block is formed merely by placing the pieces into cooperating relation and forcing the fasteners into the recesses whereupon the bars bite into the pieces and hold them together as a unit block. The production of such an improved fastener and its cooperating relation with the block pieces comprises another object of the invention.

A further feature of the invention relates to the laying of the blocks to form the flooring and embodies the use of clips or fasteners similar to those above described. These fasteners are constructed from flat metal strap material merely by cutting the latter into short lengths, bending the intermediate portion thereof into V-shape and perforating such portion to receive a nail. The blocks are recessed or grooved across their ends, as well as along the side edges, and are held securely in place by these fasteners, the ends of the fasteners extending into the grooves

of the adjacent blocks and the fasteners being held in place by nails driven therethrough and into a substructure. These improved fasteners are not only relatively simple and inexpensive but are easy to use and they hold the blocks snugly in contact with each other and down onto the substructure, all as hereinafter described. Such an improved fastener and its cooperation with the flooring pieces comprises a further object of the invention.

These and other features of the invention will be best understood and appreciated from the following description of a preferred embodiment thereof, selected for purposes of illustration and shown in the accompanying drawing, in which

Fig. 1 is a perspective view of a parquet flooring constructed in accordance with my invention;

Fig. 2 is an enlarged sectional view taken on line 2—2 of Fig. 1;

Fig. 3 is a perspective view of my improved fastener for securing the parquet block pieces together;

Fig. 4 is a perspective view of my improved fastener for securing the blocks together;

Fig. 5 is a perspective view of one of the block forming pieces;

Fig. 6 is a fragmentary perspective view of strip flooring embodying the invention;

Fig. 7 is an enlarged sectional view taken on line 7—7 of Fig. 6; and

Fig. 8 is a perspective view of a modified form of block forming fastener.

In Figs. 1—5 of the drawing I have illustrated my invention as embodied in the construction of an improved parquet flooring. This flooring, as illustrated, is made up of square blocks 10 each comprising four independent pieces 12 in edge to edge relation. Each piece 12 is recessed or grooved at 14 on both edges thereof and at its ends 16, the recessing preferably being continuous around the piece and located relatively adjacent to the bottom face thereof. Such construction leaves a relatively thick wearing portion 18 above the groove and a sufficiently thick supporting and holding portion 20 below the groove. The pieces, as illustrated, are so proportioned that four pieces placed in edge to edge relation form a square block, although it will be understood that the invention is not limited in this respect.

In accordance with my invention, the blocks 10 are conveniently formed by the use of the novel clip or fastener 22 shown in Fig. 3. This fastener is a relatively short piece of flat strap

material, of metal or the equivalent thereof, having its body portion substantially in a single plane and having inwardly projecting barbs 24 struck preferably from the interior of the end portions thereof and projecting outwardly of said plane. As illustrated, the barbs 24 are so cut from the strap that the inner end and side edges of each barb is free and the outer end is integral with the strap. Such construction provides a 10 barb which can easily be forced into the grooves 14, the opposed walls of the grooves being substantially parallel whereby to receive the fasteners with an opposed wedging action. The four pieces 12 are assembled into a block unit by 15 placing the pieces in edge to edge relation and then forcing the fasteners longitudinally of the joints 23—25 into the opposed grooves 14 whereupon the barbs bite into the body portion of the pieces and prevent any separation thereof. The 20 cooperating edges of the pieces are preferably so constructed that the adjacent pieces come into contact at both sides of the grooves, as shown at 23 and 25 in Fig. 2, thus strengthening the block at the joints and reinforcing the fasteners, although if desired the adjacent edges below the 25 grooves may be spaced apart as are the joints at 52 or the joints shown in Patent No. 1,779,729. I have found that two rather widely spaced fasteners between each two adjacent pieces and located 30 adjacent to the ends of the pieces serve to hold the pieces securely together and form a unit block of great rigidity. The barbs 24 are preferably projected from one face only of the fastener whereby to engage only the thick body portion 35 of the pieces above the fastener as shown in Fig. 2.

It will be understood that in Fig. 3 I have illustrated a specific and preferred form of fastener and that the invention is not necessarily limited thereto. For example, in Fig. 8 I have illustrated a modified form of like fastener embodying a short metal strip 26 having the ends 28 thereof turned inwardly to provide barbs 40 adapted to perform the function of the barbs 24 above described. The barbs in both forms of 45 fastener are integral with the fasteners at their rear ends only and have forward ends engaging the pieces above the grooves along a line contact substantially parallel with the adjacent 50 edges of the pieces.

As shown in Figs. 1 and 2, the blocks are laid as flooring or the like by being placed in edge to edge relation and are secured to a substructure by the use of the novel clip or fastener 30 shown 55 in Fig. 4. This fastener is a relatively short piece of flat metal strap material having its intermediate portion 32 bent out of the plane of the strap to V-shape and having the two ends substantially in the same plane for engaging within the 60 grooves of adjacent blocks, the intermediate portion having a nail receiving hole or holes 34 preferably through one or both sides thereof. The ends of the pieces 12 comprising the block 10 are grooved at 16 to receive these fasteners, 65 as are also the outer edges 36 of the outer pieces 12 of the block. These grooves are like grooves 14 except that the lower walls 38 are inclined downwardly-outwardly to a configuration corresponding substantially to the outer surfaces of 70 the intermediate V-portion 32 of the fastener 30.

In laying the blocks as shown in Fig. 1, fasteners 30 are inserted into the recesses at 36 or 16 of the block or blocks in place on the substructure, the fasteners being suitably spaced apart, 75 and holding nails 40 are driven through the holes

34 beneath the laid block. Each such nail is driven angularly in the direction of the laid block, as shown in Fig. 2, and thus crowds the fastener and laid block both laterally into contact with the adjacent block and downwardly onto the substructure. The adjacent block is laid by inserting its recess 36 over the projecting ends of the secured fasteners, as will be understood. This latter block is, thereafter crowded tightly against its cooperating block, and during 10 this movement the inclined surface 38, coacting with the inclined surface 32 of the fasteners, serves to crowd the forward edge of said latter block down onto the substructure. Thus the two adjacent edges of the block are brought and 15 snugly against each other and against the substructure.

It will now be apparent that I have produced a new and improved flooring embodying parquet blocks of a superior construction and relatively 20 simple and inexpensive fasteners cooperating therewith to hold the pieces of each block secured together into a unit, it being understood that the construction not only requires a minimum of expense for material but also a minimum 25 amount of labor to assemble the same. The invention furthermore provides a like procedure and economy for the laying of the blocks and produces a floor superior to like floors heretofore known. 30

It will be understood that my invention is not limited to the specific flooring showing in Figs. 1-5 and above described, and in Figs. 6 and 7 I have illustrated an application of the invention to strip flooring. In this construction the strips 35 50 are grooved longitudinally at 52 in the same manner as the blocks are grooved at 36—38 whereby to adapt the edges of the strips to receive the fasteners 30. The operation of laying these strips is the same as that above described 40 in connection with the blocks 10. The fasteners are inserted at suitably spaced intervals into the grooves 52 of the last laid strip and nailed as at 54. The next strip is then applied to the outwardly projecting ends of the fasteners, as will 45 be understood. When completed, the flooring strips are held securely in contact with each other and tightly against the substructure, it being understood that the nail draws and holds the apex of the V-portion 32 of the fastener tightly 50 against the substructure. It will be apparent that this securing fastener, of upright U or V-shape in cross section transversely of the juxtaposed side edges of the pieces held by the fastener, as shown in Figs. 2 and 7, is extremely simple 55 and economical, effectively serves the holding function and is convenient and easy to use.

Having thus described my invention, what I claim as new and desire to secure by Letters Patent is:

1. A parquet flooring block comprising a plurality of pieces in edge to edge relation and having their cooperating edges recessed between the top and bottom faces of the pieces to receive holding fasteners common to adjacent pieces, a plurality of fasteners engaging within and holding the adjacent pieces together, said fasteners each comprising a strip of metal having the ends thereof extending into the recesses of two adjacent pieces, and barbs on the end portions of 70 the fasteners in biting engagement with the pieces above the recesses, the sum of the widths of the fasteners along the cooperating edges of two adjacent pieces being less than one-half the length of the pieces along said edges. 75

2. A parquet flooring block comprising a plurality of pieces in edge to edge relation and having their cooperating edges recessed between the top and bottom faces of the pieces to receive holding fasteners common to adjacent pieces, a plurality of fasteners engaging within and holding the adjacent pieces together, said fasteners each comprising a strip of metal having the ends thereof extending into the recesses of two adjacent pieces, and inwardly extending barbs struck from and bent out of the plane of the end portions of the fasteners, the barbs being integral with the fasteners at their rear ends only and having forward ends engaging the pieces above the recesses along a line contact substantially parallel with the adjacent edges of the pieces. 5
3. A one-piece fastener for securing together the pieces of parquet block flooring, comprising a flat metal strap having its body portion substantially in a common plane and having an inwardly projecting barb struck therefrom at each end portion thereof and projecting outwardly of said plane, the inner end and side edges of each barb being free, the outer end be- 10
- ing integral with the strap and said inner free end presenting a line abutment for contacting with the flooring. 15
4. A parquet flooring block comprising a plurality of oblong pieces in edge to edge relation longitudinally and having their cooperating edges recessed inwardly and forming substantially parallel opposed walls between the top and bottom faces of the pieces to receive holding fasteners common to adjacent pieces, the recesses being located nearer to the bottom face whereby leaving a relatively thick and continuous wearing portion above each recess, and two fasteners respectively located adjacent to the ends of the pieces and engaging within and holding each two adjacent pieces together, said fasteners each comprising a strip of metal having the ends thereof extending into the recesses of two adjacent pieces and the sum of the widths of the fasteners along the cooperating edges of two adjacent pieces being less than one half the length of the pieces along said edges. 20
